ADJUSTABLE STAGING

Olav Aukland, New York, N. Y.

Application August 6, 1945, Serial No. 609,309

1 Claim. (Cl. 304—2)

(Granted under the act of March 3, 1883, as
amended April 30, 1928; 370 O. G. 757)

1

This invention relates to stagings and platforms and more particularly to an adjustable staging to be used by the various artisans and workers who have to do work on vertically inclined surfaces, such as the sides of a ship.

An object of this invention is to provide a staging which can be adjusted to fit the inclination that a surface or structure makes with the vertical.

Another object is to provide an adjustable staging with various platforms to accommodate workers at different levels above the base of said adjustable staging.

Another object is to provide a simple adjusting means for effecting the inclination of said staging from the vertical.

Further objects and advantages of this invention as well as its construction, arrangement and operation will be apparent from the following description and claim in connection with the accompanying drawings, in which,

Figure 1 is an isometric view of an embodiment of this invention.

Figure 2 is a side elevation view showing the staging inclined to the right of the vertical with the ladder omitted to clarify the showing.

Figure 3 is a cross section taken along the line 3—3 of Figure 1, and

Figure 4 is an enlarged view of the threaded member at the foot of the staging forming a part of this invention.

Referring to Figure 1, there is shown a base 10 which supports an adjustable staging consisting of oppositely spaced horizontal members 11 and 12 fixedly secured to the base 10, and two pairs of vertical stanchions 13, 14, 15 and 16 oppositely disposed on the surface of horizontal member 11. The feet of the stanchions 13 and 14 are pivotally secured to the horizontal member 11 by any suitable means, and stanchions 15 and 16 are similarly secured to the horizontal member 12.

The top of stanchion 14 is broadened into a head 17 having an offset guide member 18 secured thereto to engage a bar 19, said bar 19 having shoulders 20 to prevent slight slippage of the bar 19. The foot of the bar 19 is threaded so as to engage a threaded bolt or turn-buckle 21 which is pivotally mounted at the same junction where the vertical stanchion 13 is pivoted to the horizontal member 11. The top of the bar 19 is bent into the form of a handle 22 to facilitate the turning of the bar 19.

A supporting member 23 is pivotally mounted at its foot to the inside face of the horizontal

2

member 11, said supporting member 23 rising at an angle with the vertical to pass through a guide plate 24 (Figure 4) which is suitably secured by bolts 25 or equivalent means to the inside face of the head 17. A threaded handle 26 (Figure 3) passes through a threaded opening of the guide plate 24 and is attached to a friction plate 27. By turning the handle 26, the friction plate 27 is urged forward to frictionally lock the supporting member 23 to the stanchion head 17.

Supporting member 28, guide plate 29, handle 30 and broadened head 31 are similar to and serve the same function as supporting member 23, guide plate 24, handle 26 and head 17. Likewise the bar 32 having its upper extremity bent to form a handle to facilitate the turning of bar 32 corresponds to the bar 19.

A guide member for supporting the bar 32 and a threaded bolt for engaging the threaded foot of bar 32 is obscured by supporting structure but it should be obvious that they are secured, respectively, to the outer face of the head 31 and to the pivoted joint at the foot of stanchion 15.

The horizontal platforms 32 and 33 are suitably secured to the stanchions 13, 14, 15 and 16, the dovetail fitting between platform and stanchions for this embodiment of the invention being more clearly shown in Figure 2. The horizontal braces 34 and 35 are suitably mounted in stanchions 13 and 14 and serve to support said stanchions against lateral stresses. Horizontal members 36 and 37 brace the stanchions 15 and 16.

Thus it will be evident that the staging is of symmetrical construction save for a ladder 38 which may be secured to either end of the staging. The ladder 38 is rigidly but detachably secured to offset members 39 and 40 that are, in turn, secured to a horizontal brace 35, the ladder being secured to the offset members 39 and 40 so as to permit the ladder 38 to hang down away from the bar 19.

In the operation of the adjustable staging the supporting member 23 is disengaged from the head 17 by turning the handle 26, then the bar 19 is rotated in clockwise or counterclockwise direction, depending upon whether the staging is to be inclined forward or backward from the vertical. The handle 26 is then turned to frictionally lock the supporting member 23 to the head 17 in the adjusted position of the staging. Meanwhile another operator is at the other end of the staging performing the same adjustments as those just described.

This invention is conveniently used by painters who have to do work on the sides of a ship, especially near the bow or stern. The entire staging can be lashed securely to a floating base or barge adapted to be anchored near a ship or moored thereto, the sides of said ship being inclined to the vertical, said inclination being different for different sections of the ship. In conventional stagings where the rigging or staging is fixed, certain painters on all levels but one are too far from the ship's side as the fixed staging is moved, in its entirety, from one section to another section of the ship. Painters who are on platforms too far from the ship's side cannot paint accurately or comfortably, and accidents are likely to occur.

The description of the adjustable staging of the present invention for use in the painting of a ship's side is only one example of its use, and does not necessarily restrict the wider application of this invention. The staging can be used as a supporting structure for artisans working on large scenery props in a theatre, on billboards and advertising signs; in fact, in any situation where the surface to be worked upon is inclined to the vertical. When some surfaces in a given work area are vertical and others are inclined to the vertical, the same staging can be used, thus diminishing the number of stagings that have to be constructed by contractors for a given building or other construction.

25

30

It is to be understood that various modifications and changes may be made in this invention without departing from the spirit and scope thereof as set forth in the appended claim.

5 The invention described herein may be manufactured and used by or for the Government of the United States of America for governmental purposes without the payment of any royalties thereon or therefor.

10 What is claimed is:

A base adapted to float upon a liquid surface, a vertically disposed supporting structure secured to said base, multiple horizontal platforms secured at spaced intervals along said supporting structure, multiple braces pivotally secured at an angle to said base and slidably secured to said vertically disposed structure, said braces serving to buttress said vertically disposed supporting structure, turn-buckles pivotally secured to said base along the sides of said supporting structure, rotatable rods disposed diagonally along said vertically disposed framework and engaging said turn-buckles, the turning of said rotatable rods changing the inclination of said vertically disposed supporting framework, means to rigidly hold said rotatable diagonally disposed rods to said vertically disposed structure, and locking means to secure said framework after the required angle of inclination has been obtained.

OLAV AUKLAND.
